SASH CONSTRUCTION

Christian M. Verhagen, Elkhart, Ind., assignor
to The Adlake Company, Chicago, Ill., a cor-
poration of Illinois

Application November 22, 1935, Serial No. 51,046

5 Claims. (Cl. 189—76)

In the production of metal sash of the vertically slidable type used in railway cars, busses and other vehicles, it has been the usual practice to make all the rail members of sheet metal with the ends of the members mitered and connected together at the corners by means of L-shaped reinforcing inserts secured within the hollow mitered ends of the members.

This arrangement is satisfactory where sheet brass, for instance, is employed as the metal, but where sheet aluminum is substituted, difficulty has been experienced in obtaining sufficient strength, the bottom rail of the sash being inclined to give somewhat under the strains to which the same is subjected in being grasped to raise or lower the sash in snugly fitting guides. In an attempt to overcome this difficulty and at the same time retain the advantages inherent in aluminum, some sash have been made with the rail members of extruded aluminum, but this type of structure, while giving ample strength, has been too expensive to be entirely practicable.

The object of the present invention is to provide an improved aluminum sash structure which is inexpensive to manufacture and yet possesses all of the advantages of an extruded aluminum structure.

Other more specific objects and advantages of the invention will be apparent to those skilled in the art upon a full understanding of the construction and manner of assembly of the new sash.

Two different forms of the invention are presented herein for the purpose of exemplification, but it will of course be appreciated that the invention is capable of being embodied in other structurally modified forms coming equally within the scope of the appended claims.

In the accompanying drawings:

40 Fig. 1 is an inside face view of one of the lower corners of a sash constructed in accordance with the invention;

45 Figs. 2 and 3 are different perspective views, showing the way in which the ends of the side and bottom rails are brought together, fitted and welded;

Fig. 4 is a vertical section through the median plane of the completed corner;

50 Fig. 5 is a horizontal section through the side rail, taken on the line 5—5 of Fig. 4;

Fig. 6 is a vertical section through the bottom rail, taken on the line 6—6 of Fig. 4;

55 Fig. 7 is a perspective view showing in separated relation the parts involved in the forma-

tion of a somewhat different corner which also embodies the invention; and

Fig. 8 is another perspective view of the same corner in completed condition, with the bottom rail sealing strip and a portion of the side rail bearing strip removed for clearness.

In the sash which is illustrated in Figs. 1 to 6 inclusive the side rail 10 is made of thin sheet aluminum while the bottom rail 11 is made of relatively thick extruded aluminum. The bottom rail 11 extends the full width of the sash, and its ends cut off at right angles flush with the side edges of the sash.

The rails 10 and 11 are of the same thickness and contain glazing grooves 12 and 13 of the same size, but the side walls 14 along the sides of the glazing groove in the rail 10 are hollow while the corresponding side walls 15 along the sides of the glazing groove in the rail 11 are solid. The lower end of the side rail 10 is cut off at right angles and is seated on the upper edges of the side walls 15 of the rail 11, in which position the rails are welded firmly together, filleted at 16 with additional weld deposits and polished off flush to give the smooth one-piece appearance shown in Fig. 1.

The extruded bottom rail 11 is formed with a groove 17 along the lower edge thereof for the reception of a rubber sealing strip 18, and a longitudinally extending cross web 19 is provided in the rail 11 at the back of the groove 17 in spaced relation to the back of the glazing groove 13 for the purpose of reinforcing the rail and completing a suitable tubular support for a slidably mounted locking bolt 20.

By cutting off the end of the rail 11 squarely at right angles flush with the back of the rail 10 the ends of the grooves 13 and 17 in the rail 11 are left open and the space between the back of the glazing groove 13 and the cross web 19 is 40 also left open. This facilitates drainage of the groove 13, affords easy insertion of the bottom rail sealing strip in the groove 17 and permits introduction of the locking bolt 20 into the space present in the rail above the cross web 19.

By forming the corner in this fashion, with the lower end of the rail 10 cut off squarely and butted solidly on the parallel upper surfaces of the side walls 15, no corner reinforcement is needed, no special shaping or mitering of the ends 50 is required, and a strong joint of pleasing appearance free of rivets and visible joints is produced.

In the modification which is shown in Figs. 7 and 8 the side rail 21 is provided with a special groove 22 for the reception of a rubber strip 23.

35

30

35

40

45

50

55

This strip works in the guide at the side of the window and constitutes a resiliently yieldable extension for the side rail, in accordance with the disclosure in Hamm Patent No. 1,981,355.

5 The side edges of the groove 22 have inturned flanges 24 which hold the strip 23 in proper position.

As the groove 22 with its inturned flanges 24 should extend all of the way down to the bottom 10 of the sash in order to obtain full benefit from the strip 23, a sheet metal insert 25 which is shaped to form a continuation of the groove and the flanges is fitted into a milled-out recess 26 in the end of the extruded aluminum bottom rail 15 27 and is welded in place at one or more points. The insert 25 is characterized by a groove 28 and inturned flanges 29. It is open at its ends, and both the back of the insert and the inturned flanges are cut away to provide a passageway 20 30 for the end of a locking bolt.

As in the first described embodiment of the invention the bottom rail 27 is cut to the full width of the sash and the lower end of the side rail 24 is cut off at right angles, placed on the 25 upper edges of the side walls 31 of the glazing groove in the bottom rail and welded in position.

While the herein described joint construction is particularly applicable to aluminum sash structures wherein the side rails are of sheet aluminum and the bottom rail is of extruded aluminum, it will of course be understood that the joint construction and the other associated features can be employed to advantage in sash structures where the side rails, like the bottom rail, are made of extruded aluminum, and also where the side rails and bottom rail are made of other metals.

I claim:

40 1. In sash construction, side rails consisting of thin sheet aluminum members and a bottom rail consisting of an extruded aluminum member which contains a longitudinally extending cross web, said bottom rail member being cut vertically at its ends to the full width of the sash, and said side rail members being welded at their lower ends to the upper edges of the bottom rail member above the cut ends of the latter, leaving the cut ends open for the reception and support of a locking bolt on the cross web.

45 2. In sash construction, an extruded aluminum bottom rail of hollow formation which extends

the full width of the sash and is cut vertically at its ends flush with the side edges of the sash, and thin sheet aluminum side rails of hollow formation which are of the same overall thickness as the bottom rail and are welded to the bottom 5 rail above the cut ends of the latter, leaving openings in the cut ends of the bottom rail for the reception of the locking bolts.

3. In sash construction, an aluminum bottom rail cut to the full width of the sash, aluminum 10 side rails cut at their lower ends and welded along the cuts to the upper edge of the bottom rail flush with the ends of the latter, the outer edges of the side rails being provided with grooves with inturned edges for the reception of rubber bearing strips, and aluminum inserts of substantially the same cross sectional shape as the grooves in the outer edges of the side rails, which inserts are secured in milled-out recesses in the cut ends 15 of the bottom rail.

4. In a vertically slideable sash, a metal bottom rail provided along its upper edge with spaced glazing groove walls of the same height, and metal side rails provided along their edges with similarly spaced glazing groove walls of the same 25 height, the ends of the bottom rail being cut vertically to the full width of the sash, and the lower ends of the side rails and the glazing groove walls thereof being cut off in a horizontal plane and welded along the cut surfaces to the upper 30 edges of the glazing groove walls in the bottom rail.

5. In a vertically slideable sash, a metal bottom rail provided along its upper edge with spaced glazing groove walls of the same height, 35 and metal side rails provided along their edges with similarly spaced glazing groove walls of the same height, the ends of the bottom rail being cut vertically to the full width of the sash, and the lower ends of the side rails and the glazing groove 40 walls thereof being cut off in a horizontal plane and welded along the cut surfaces to the upper edges of the glazing groove walls in the bottom rail, the glazing groove walls of the bottom rail being solid, and the glazing groove walls 45 of the side rails being hollow, with the exposed surfaces of the hollow walls flush with the exposed surfaces of the solid walls both on the inside of the glazing grooves and on the outside of the rails.

CHRISTIAN M. VERHAGEN.
